RAILWAY CAR

Garth G. Gilpin, Riverside, and Arthur E. Small, Chicago, Ill., assignors, by mesne assignments, to General Steel Castings Corporation, Granite City, Ill., a corporation of Delaware

Original application April 8, 1929, Serial No. 353,494. Divided and this application July 15, 1931. Serial No. 550,936

10 Claims. (Cl. 105—249)

The invention relates to railway freight cars and particularly that class of equipment known as "hopper cars" wherein the lower portion of the car body comprises a plurality of hoppers.

5 These hoppers are disposed on the opposite sides of the center construction of the car and cross bearers are positioned between adjacent hoppers which are secured to the opposite side walls of the car and also connected to the center construction. Some cars have just one cross bearer, while others have a plurality of cross bearers with hoppers disposed on both sides thereof.

In such types of cars the moisture in the lading, due to rain, melting snow, thawing of the material, etc., accumulates adjacent the bottom part of the lading so that that part of the lading in contact with the hoppers, center construction, cross bearers and other associated parts becomes wet and holds the moisture in contact therewith causing excessive corrosion when these parts are made of rolled steel, especially if such rolled steel parts have been deformed by pressing. It is common practice to use such cars for transporting coal and when moist coal, particularly 20 coal dust, is allowed to remain in contact with the rolled steel parts, the acid formed thereby eats into the steel parts.

Such corrosive and acidic action rapidly eats away the rolled steel and experience shows that 30 these hoppers and associated parts must frequently be replaced, which is expensive, not only from material and labor cost, but also by keeping the car out of service.

An object is to eliminate the cost and delay 35 in fabricating the numerous component parts of the present structural steel car parts.

Another object of forming the car part of cast metal is to eliminate the possibility of loose connections which would permit relative motion 40 between the component parts of the car part, as it is common knowledge that the vibration of the car in motion, due to rough and uneven track, and steel wheels rolling on steel rails, together with longer trains and high speeds in present day practice, cause riveted joints and built up sections to work loose and the railroads look with favor upon any device which reduces the 45 number of parts and joints as these are the weak parts of the car and the more such weak parts are eliminated, the longer the life of the car.

In the drawings:

Fig. 1 is a cross section of a car including my improvement.

55 Fig. 2 is a fragmentary side elevation of the car.

Fig. 3 is a fragmentary longitudinal section of the car.

Fig. 4 is a fragmentary longitudinal section of Fig. 5.

Fig. 5 is a cross section of a car showing a modification of my improvement.

In a "hopper car" of the type described above the load is carried to the body bolsters 2 by the center sills 3 or center construction 4 and the side walls 5. The center construction usually 65 comprises spaced apart center sills 3 of rolled steel sections and a rolled steel cover plate 6, which sills and cover plate extend between the body bolster and usually therebeyond to accommodate the draft gear. The side walls may be 70 of a truss or a girder design. In the form illustrated the top (7) and bottom (8) chords of the side girder are connected by the web plate 9 which also is the load retaining means of the side wall. To meet strength requirements it is 75 preferable to make the top and bottom chords of rolled steel. In order to save weight and material it is desirable to make the web plate also of rolled steel.

The construction shown in Figs. 1 to 3 inclusive consists of an integral casting comprising a hopper on each side of the center construction, a center construction hood and part of a cross bearer. Two of such castings (preferably duplicates) are secured together to form the 85 complete hopper part of the car, which united castings are then merely secured to the center construction and opposite side walls of the car. Each part of the cross bearer comprises a web plate 13 with the upper stiffener 14 and oppositely disposed sloping lower portions 15 which direct the discharging lading into the hopper. The cross bearer is arranged to protect the lower side chord 8 and the lower portion of the web plate 9 from the lading. The cross bearers straddle the center construction 4 and are secured thereto in any convenient manner. We also prefer to cast hinge lugs 16 integral with this cross bearer to support the hopper door 17. The brace is secured to the side wall and also to the 95 outer end of the cross bearer 12 and comprises a diagonal member 18 extending from adjacent the top of the side wall to substantially the middle of the cross bearer. It is also provided with an extension 19 connected to the upper chord 7 to brace that member against deflection. The 100 hoppers 20 on opposite sides of the cross bearer are preferably cast integral therewith. These hoppers comprise an inclined portion 21 with oppositely disposed substantially upright por- 105

tions. The inner (22) of said upright portions is connected to the center sill and arranged to protect it from the lading. The outer (23) of said portions is connected to the side wall and arranged to protect the lower chord (8) from the lading. The integral reinforcing ribs 24 extend continuously around the inclined portion and the upright portions of the hopper. The hopper is also preferably reinforced with longitudinally extending integral ribs 25 below the inclined portion.

In the construction shown in Figs. 4 and 5 the center construction comprises a pair of rolled steel channels 60 or beams (called center sills) extending between the body bolsters 61 of the car and an upper cover plate 62 secured thereto. The transom or cross bearer 63 is made of cast metal attached at one end to one of the center sills 60 (or to the center construction) and its opposite end is secured to the side wall 64 of the car. The cross bearer is provided with oppositely disposed sloping surfaces 65 to direct the discharging lading into the hopper and also has vertically disposed ribs 66 and integral hinge lugs 67 are positioned below the sloping portion and adjacent the vertical rib and cast integral therewith providing a very strong hinge lug arrangement. The upper part of the cross bearer is arranged for attachment of the bracing member 68, which arrangement, in the form shown, comprises a flat substantially horizontal upper surface 69 to accommodate the T section 70 of the brace so as to obtain two rows of rivets connecting the two elements. This brace may extend continuously from side to side of the car or be made of two members secured together by a splice plate 71, as shown in Fig. 5. The outer vertical portion 72 of the brace is secured to the side wall 64 of the car. This brace resists the tendency of the side wall as a girder to buckle and also in combination with the cross bearer 63 suspends the center construction from the opposite side walls and forms a transverse member of greater effective depth than the elements 63 or the center sills.

The accompanying drawings illustrate preferred forms of the invention, though it is to be understood that the invention is not limited to the exact details of construction shown and described, as it is obvious that various modifications thereof, within the scope of the claims, will occur to persons skilled in the art.

This is a division of our co-pending application Serial No. 353,494, filed April 8, 1929.

55 We claim:

1. In a railway car, the combination of a top chord, a bottom chord, a web plate secured to the top and bottom chords respectively consisting of a lower vertical portion and an upper inclined portion, a cross bearer having a vertically disposed upper element extending transversely of the car substantially horizontally up to said web plate and connected to said plate, hopper structure depending from said cross bearer, and a brace secured to said cross bearer element at said plate and at a point spaced from said plate, said brace also secured to said lower and upper portions of said plate.

2. In a railway car, the combination of a top chord, a bottom chord, a web plate secured to the top and bottom chords, respectively consisting of a lower vertical portion and an upper inwardly inclined portion, a cross bearer comprising a cast metal device extending normally to said plate, and a brace secured to said cross bearer away from said plate, said brace also secured to said lower and upper portions of said plate and to said top chord.

3. In a railway car, a center sill structure, a girder-like side wall, a cross bearer device of cast metal of substantially uniform depth between said sill structure and side wall, hopper structure depending from said cross bearer, and a brace device of cast metal secured to the upper and lower portions of said wall and to said cross bearer at a point adjacent said sill structure.

4. A construction as described in claim 3 in which the hopper structure is cast integrally with the cross bearer.

5. In a railway car, girder-like side walls, a cross bearer device of cast metal of substantially uniform depth extending between and connected directly to said side walls, hopper structure depending from said cross bearer, and brace devices of cast metal secured to the top of said cross bearer near the center of the car and to said side walls at points adjacent the upper portions of said side walls and at points above the top of said cross bearer.

6. A construction as described in claim 5 in which the hopper structure is cast integrally with the cross bearer.

7. A construction as described in claim 5 which also includes a center sill structure to which the cross bearer is secured.

8. In a hopper car, side walls, center sill structure, transom elements extending between said center sill structure and said side walls and having a depth approximating the depth of said center sill structure, side wall bracing elements extending substantially throughout the height of said side walls and secured thereto and having lower portions secured to said transoms at points adjacent to said center sill structure, said transoms and braces cooperating to form a U-shaped member extending from side to side of the car and from near the lower portion of said center sill structure to near the upper portion of said side walls.

9. In a railway hopper car, side walls, center sill structure, and braces for said side walls each having a lower portion extending from the respective side wall to said center sill structure and overlying the latter, said portions being secured together to form a continuous member extending from side wall to side wall.

10. A car having the structure specified in claim 9 and also including transoms on the sides of the center sill structure and extending therefrom to the side walls and secured to the braces whereby a cross bearer is formed having an effective depth greater than the depth of the center sill structure.
